SELECTIVITY ADJUSTMENT COUPLING
NETWORKRobert W. Turner, East Orange, N. J., assignor to
Federal Telephone and Radio Corporation, a
corporation of Delaware

Application May 9, 1942, Serial No. 442,336

5 Claims. (Cl. 179—171)

This invention relates to wave coupling networks and more especially to such networks as are used for tuned couplings and are of adjustable selectivity.

A principal object of the invention relates to a wave coupling arrangement for circuits which are adjustable as to selectivity while being maintained tuned to a given frequency.

Another principal object is to provide a tuned interstage coupling arrangement for high frequency amplifiers whereby a constant capacity reactance is maintained in the resonant circuits while permitting adjustment as to selectivity.

Another object is to provide an improved coupling arrangement for the intermediate frequency amplifier section of a superheterodyne receiver or the like which coupling arrangement is adjustable as to selectivity while maintaining the resonant frequency constant.

A feature of the invention relates to a plural stage wave amplifier wherein the interstage coupling is of adjustable selectivity while being maintained at a desired resonant frequency, in conjunction with specially designed switch means to compensate for change of gain tending to result from changes in selectivity.

Another feature relates to a tuned coupling arrangement particularly well suited to couple the stages of an intermediate frequency amplifier, wherein the tuned unit is divided into a plurality of tuned sections which are capacitively coupled, the coupling capacity being so arranged that the degree of coupling can be varied to vary the selectivity, while the tuning is not materially affected.

A further feature relates to a tuned coupling arrangement for intermediate frequency amplifiers wherein the tuning capacities of two resonant circuits consists of two sections in series, one of which sections is common to the two resonant circuits, and which is in the form of a condenser bank and provided with a switching means whereby the shunt-series combination of the condensers can be varied.

A still further features relates to the novel organization and interconnection of parts which constitute an improved intermediate frequency coupling arrangement for superheterodyne receivers and the like.

Other features and advantages not particularly set forth will be apparent after a consideration of the following descriptions and the appended claims.

While the invention will be described as embodied in an intermediate frequency amplifier of a superheterodyne receiver, it will be under-

stood that such is done merely for explanatory purposes and not by way of limitation to such uses or to the specific apparatus and parts referred to. Accordingly in the drawings,

Fig. 1 is a schematic circuit diagram of a portion of a wave amplifying system embodying the invention.

Figs. 2, 3 and 4 are respectively simplified schematic diagrams of the coupling and tuning sections of Fig. 1 in three different operational settings.

Referring to Fig. 1, there is shown in schematic detail the intermediate frequency amplifier portion of a superheterodyne receiver wherein the incoming intermediate frequency signal from the line L, which is connected to the output of a mixer or converter tube, after passage through a tuned selective circuit 1, is impressed upon the control grid 2 of an amplifier tube 3. The plate 6 and the screen grid 5 are supplied with steady potentials from the positive terminal 7 of a suitable battery or power supply. The third or suppressor grid 8 is connected to the cathode 9 and thence to ground through the section 10 of a gang switch and thence through one or more sections of the gain control bias resistors 11, 12, 13, which are shunted by the usual by-pass condenser 14.

The resistor 10 is to complete the direct current path from grid to ground and has no effect on the performance of the tuned circuits or coupling circuits. Also, a by-pass condenser 15 is connected from grid 5 and the low potential end of the inductance 21 to ground.

As a result of the connections above described, the incoming intermediate frequency signal is amplified by tube 3, which is coupled to succeeding I. F. amplifier and detector and audio amplifier stages represented schematically by the block 16. The output of 16 is applied to any form of load circuit 17.

In such systems, it is highly desirable to be able to vary the selectivity of the coupling between the amplifier tube 3 and the succeeding stages 16. However, when varying the degree of selectivity it is desirable that the intermediate frequency tuning should be maintained constant, and at the same time it is desirable to maintain a uniform overall gain in the amplifier system. Accordingly, I have devised a novel form of coupling and switching arrangement whereby these desirable results are obtained. For this purpose, the coupling unit between the tube 3 and the stage 16 comprises a network divided into a plurality of units 18, 19, 20, each unit including a

tuning inductance coil 21, 22, 23, with associated tuning condenser sections; one section for each coil comprising a fixed condenser 24, 25, 26, and its parallel trimmer condenser 27, 28, 29; the other section for the coils consists of two banks of fixed condensers 30, 31, 32, and 34, 35, 36.

The condenser bank consisting of condensers 30, 31 and 32 is adapted to be connected between the condensers 24, 27 and 25, 28, in various combinations to provide different coupling coefficients between the units 18 and 19. This variable connection of the condenser bank is under control of the section 33 of the gang switch. Likewise, the condenser bank consisting of condensers 34, 35, 36, is adapted to be connected in various combinations and mutual coupling relations between the condensers 28, 29 and 26, 29 under control of the section 37 of the gang switch. It will be understood that the switch sections 10, 33 and 37 are operated as a unit from a common control shaft as indicated by the dot-dash connecting line shown in Fig. 1.

The gain control switch section 10 has a set of brushes 38-42 which cooperate with a rotatable metal commutator 43 adapted to assume three different positions. In the first position as shown, cathode 9 is connected to ground through resistor 11, brush 39, segment 43, brush 41, resistor 13. In the second position of the switch, cathode 9 is connected to ground through resistor 11, brush 39, commutator 43, thence in parallel through brushes 40 and 41 and resistors 12, 13. In the third position, cathode 9 is connected through resistor 11, brush 39, segment 43, brush 38 to ground. Thus in the three successive positions of switch section 10, the negative bias of grid 2 is reduced whereby the gain of tube 3 is correspondingly increased.

The condenser bank 30, 31, 32, is connected to switch section 33 so that the coupling coefficient between condensers 24, 27 and 25, 28 is decreased in three successive steps; and likewise switch section 37 connects the condenser bank 34, 35, 36, in various combinations, so that the coupling coefficient between condensers 28, 29 and 26, 29 is likewise decreased in three steps. This decrease in coupling tends to result in a proportionate reduction in gain in the output of the amplifier. However, since the gain of tube 3 is increased in proportion to the reduction in gain in the coupling network, the overall gain of the amplifier remains uniform while allowing the changes in selectivity. In order to accomplish this, it is necessary to proportion the condensers of each bank properly with respect to each other and with respect to the associated condensers 24-27, 25-28, 26-29, so that the overall capacity reactance in the coupling network remains uniform while reducing the coupling coefficient. The manner in which the various condensers of the coupling network are connected into circuit in the three positions of the gang switch are represented schematically in Figs. 2, 3, and 4. Referring to Fig. 2, it will be noted that the coupling coefficient between the circuits 18 and 19 is controlled by the series condenser combination 32 and 31. Similarly the series condenser combination 36 and 35 controls the coupling coefficient between circuits 19 and 20. The tuning of each circuit is at the desired intermediate frequency. In position 2 of the switch as shown in Fig. 3, the condenser 30 of the first bank is connected between ground and the junction of condensers 32 and 31, and controls the coupling coefficient. Condensers 32 and 31 are connected in series with condensers

27 and 28, respectively, for the purpose of maintaining constant tuning. A similar arrangement applies in the case of the circuits 19 and 20 and the second bank of condensers except that condenser 35 is short-circuited.

In the third position of the gang switch (Fig. 4), the condensers are connected in the same general relation as in Fig. 3 with the exception that the coupling condensers 32 and 36 are of higher capacity than the corresponding coupling condensers in Fig. 3 and hence the coupling coefficients are reduced.

In order that the switching function of the two switch sections 33 and 37 may be clearly understood, the parts of Fig. 1 corresponding to those in Figs. 2, 3 and 4, bear the same designation numerals. When the gang switch is in position 1 as shown in Fig. 1, the conductor 38 is directly and conductively connected to the conductor 39 via brush 44, commutator segment 45, brush 46. The common direct connection between conductors 38 and 39 is returned to ground via brush 47, segment 48, brush 49, condenser 32, strap 50, condenser 31, brush 51, segment 52 and brush 53. Likewise, conductor 54 is directly connected to conductor 55 via brush 56, segment 57 and brush 58. This direct connection between conductors 54 and 55 is returned to ground via brush 59, segment 60, brush 61, condenser 36, strap 62, condenser 35, brush 63, segment 64 and brush 65. In second position, conductor 38 is connected to conductor 39 through two condensers 31, 32, in series as follows. Conductor 38, brush 47, segment 48, brush 49, condenser 32, strap 50, condenser 31, brush 51, segment 45 and brush 46. The common connection between condensers 31 and 32 is connected to ground through condenser 30 via brush 66, segment 52, brush 53. Likewise, in second position of section 37, conductor 54 is connected to conductor 55 but only through condensers 36 since condenser 35 is short-circuited at 68 and 57 and the common connection of these two condensers is returned to ground through condenser 34. In the third position of the switch, conductor 38 is connected to conductor 39 through the two condensers 30 and 31 in series as follows. Conductor 38, brush 47, segment 48, brush 67, condenser 30, condenser 31, brush 51, segment 45, brush 46, conductor 39. The common connection between condensers 30 and 31 is returned to ground through condenser 32 via brush 49, segment 52, brush 53, brush 66, segment 52. Merely for illustration, condensers 30, 31 and 34, 35, may each be of .01 mfd. while condensers 32 and 36 can be .02 mfd. It will be understood of course that any other values of the condensers may be employed so that in conjunction with the remaining electrical constants of the coupling network, the capacity reactance remains substantially constant while varying the effective capacity coupling between the various sections of the network. It will be understood of course that while the invention shows an amplifying system employing a single intermediate frequency amplifying stage, between the amplifier 3 and the first intermediate frequency amplifier tube, a plurality of similar stages may be employed. Thus, the output of the I. F. amplifier tube may feed a second I. F. amplifier having a series of network sections in its output circuit similar to sections 18, 19, 20 and these sections being provided with tuning arrangements and switch sections similar to sections 33 and 37 in which event these additional sections may be operated from the same 75 gang shaft as the sections 10, 33 and 37.

Various changes and modifications may be made in the disclosed embodiment without departing from the spirit and scope of the invention.

What I claim is:

1. A tuned coupling arrangement for electric wave amplifiers comprising a pair of tuning inductances, each having a high potential end and a low potential end, a pair of tuning condensers, one end of each is connected to said high potential ends, a bank of fixed condensers for supplementing said pair of condensers in tuning said inductances, and plural-position switch means effective in one setting to connect said pair of condensers directly in series between the said high potential ends while connecting a plurality of condensers of said bank from the common junction of said pair of tuning condensers to said low potential ends, said switch means being effective in another setting to connect one condenser of said bank in series between said pair of tuning condensers.

2. A tuned coupling arrangement for electric wave amplifiers comprising a pair of circuits to be coupled, each including an inductance and a tuning condenser, a bank of fixed condensers, and a multi-position switch effective in one setting to connect the condensers of said bank in simple series-shunt across the high and low potential terminals of the coupling circuit and effective in second and third settings to connect the condensers in said bank in a T or shunt-series relation across said ends, the second and third settings producing different degrees of selectivity in the coupling as compared with the first setting but without changing the tuning.

3. An electric wave amplifier comprising a

tuned network adapted to couple two vacuum tubes in series, including two tuned sections and a variable capacitance unit coupling the sections, said unit comprising a plurality of fixed capacities and stage switch means for connecting said capacities in coupling relation to the sections to form a series of coupling capacity values, thereby varying the coupling coefficient between said sections, and the gain of the input tube; gain compensating means for simultaneously varying the gain of the input tube in the opposite sense, including a plurality of resistances and stage switch means for connecting said resistances in circuit with an electrode of the input tube to form a plurality of varying resistance values in said circuit, arranged to produce changes in the tube gain compensating for gain changes produced by similar stage variations in the capacitance unit; and means for synchronously operating both of said stage switch means arranged to maintain uniform input tube gain.

4. An amplifier as set forth in claim 3, in which the capacitance stage switch means is arranged to connect said fixed condensers in series tuning position between said sections.

5. A tuned coupling arrangement for electric wave amplifiers comprising a pair of circuits to be coupled, a condenser bank including two condensers of different capacity value, and selective switch means for connecting said bank in coupling and tuning relation to said circuits, including means for connecting either of said two condensers in series tuning relation and the other in coupling relation between said circuits.

ROBERT W. TURNER.
